UNITED STATES PATENT OFFICE.

GUS MENESEE, OF ATLANTA, GEORGIA.

BOAT RETAINING AND RELEASING DEVICE.

Application filed June 11, 1926. Serial No. 115,808.

The object of this invention is to provide means whereby the block and fall at both the bow and stern of a lifeboat, or other boat launched from the side of a ship, may be released at the same time, by the operation of a single lever, the apparatus also permitting of the release of the block and fall at one end independently of the other.

A further object is to effect this result by the use of slideable bolts adapted to engage hooks connected respectively with the axial element of each block or sheave, special means being provided for controlling the bolts and operating them together or independently, as desired.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a view showing a boat in side elevation, with the special attaching and releasing means herein disclosed, the lever operated rock shaft appearing in dotted line being adapted to release the engaging devices fore and aft at the same time.

Figure 2 is a fragmentary view in vertical section showing the manner of mounting and controlling the slideable bolt or trigger.

Figure 3 is a section on line 3—3 of Figure 2, and on an enlarged scale.

Figure 4 is a section on line 4—4 of Figure 2.

Figure 5 is a perspective view, showing a spring operated device adapted to engage the slideable element retaining the hook.

Figure 6 is a detail view showing means for rotating the gear wheel engaging the rack of Figure 2, which rack operates with the slideable element engaging the hook.

Figure 7 is a section on line 7—7 of Figure 2.

Figure 8 is a section on line 8—8 of Figure 1.

The boat 10 is suspended by blocks and falls, and the hooks 11 include shanks rotatable by handles 12 independently of the U-frames or blocks 13 which mount the sheaves 14. Springs 15 interposed between collars 16 and the U-frames, cause the hooks to clear

the retaining means when the latter are released.

Bolts 17 operating as plungers in cylinders 18 formed in housing 19 engage the hooks 11 and retain the latter, the housing 60 being inclosed to prevent so far as possible, the entrance of water and the resulting formation of ice in severe weather.

The bolts 17 include rack members 18' engaged by gear wheels 20 mounted on shafts 65 21, rotatable in bearings 22 formed in brackets 23.

Elements 21 constitute rock shafts, and movement is imparted thereto by arms 24, slotted at 25 and terminating in pedals such 70 as 26. Pressure on the pedals, imparting rotary movement to gear wheels 20 produces the release of bolts or plungers 17 from the hooks 11, thereby releasing the boat.

This construction is employed at the bow 75 and stern of the boat 10, and it will be observed that the pedals serve to control the release of either bolt or plunger 17 independently of the other, and that the plunger is normally held in engaging position by 80 spring 30 bearing against the inner end of element 17 and against a threaded and adjustable cap 31.

In order to release both bolts 17 at one time, I connect with the slotted portion 25 of each arm or lever 24, a link or the like, 33, having pivotal connection with rod 34, which in turn has connection thru a short link 35 with an arm 36 rigid with reference to rock shaft 37 extending longitudinally of 85 the boat, in the bottom thereof. This shaft 37 may be rocked by means of hand lever 38, for releasing both engaging devices 17, and therefore releasing the boat from the launching means. When either pedal 95 26 is operated, direct movement is imparted to shaft 21 and to gear wheel 20 and rack bar 18, and therefore to bolt 17, for releasing the latter. The slot 25 in arm 24 permits of 100 this independent movement.

A vertically movable element 40, shown in perspective in Figure 5, includes a concave portion 41 and ribs 42 on the side, these ribs being adapted to operate in grooves 43, serving as guides. Each element 40, termed a 105 trigger, includes a stem 44 surrounded by a spring 45, the latter imparting upward thrust to element 40, and a pin 46 passes thru slot 47 in stem 44, and acts as a retaining device. Element 40 retains bolt 17 110

when the latter is retracted, for the hook releasing operation, in which spring 30 is compressed. In the engaging operation, hook 11 presses trigger 40 downwardly and 5 frees bolt 17 which advances under spring action and engages hook 11.

Having thus described the invention, what is claimed is:

1. In apparatus of the class described, 10 boat launching means including a block and fall and a hook connected with the block, a bolt for engaging the hook, a pedal, means operatively connected with the pedal for releasing the bolt from the hook, and means 15 independently operated for releasing said bolt, and means retaining the bolt inactive, the retaining means being releasable by the hook.
2. In apparatus of the class described, 20 boat launching means including a block and fall and a hook connected with the block and rotatable with reference thereto, a bolt for engaging the hook, a spring bearing on said bolt and holding the same in operative 25 position, and rack and pinion mechanism for controlling the movement of the bolt

against the action of the spring, a pedal controlling each rack and pinion mechanism, and a rock shaft operatively connected with the pedals.

3. In apparatus of the class described, means including a hook for suspending a boat, a slideable member for engaging and retaining the hook, resiliently mounted means bearing against said slideable member at a point adjacent to the engagement thereof, by the hook, and movable across the path of the slideable member, a rack connected with the slideable member, a gear wheel engaging the rack, and devices independently operated for imparting movement to the gear wheel.

4. In apparatus of the class described, boat launching means including a plurality of hooks, bolts slidably mounted and adapted to engage the hooks, pedal operated means for throwing the bolts separately, and rock shaft operated means for throwing said bolts simultaneously to hook releasing position.

In testimony whereof I affix my signature.
GUS MENEFEE.
